UNITED STATES PATENT OFFICE.

KUMA KAWAGUCHI, OF NEW YORK, N. Y.

LAMP SHADE.

Application filed September 20, 1920. Serial No. 411,509.

To all whom it may concern:

Be it known that I, KUMA KAWAGUCHI, a citizen of the United States, residing at New York city, in the county of New York and State of New York, have invented new and useful Improvements in Lamp Shades, of which the following is a specification.

This invention comprehends the provision of a lamp shade, and has for its chief 10 characteristic the provision of a shade made up of adjustable sections which may be moved with respect to the globe to deflect the light rays in any desired direction, and the shade sections held in any given 15 position.

Another object of the invention resides in the provision of a shade of the above mentioned character, which is simple in construction, to facilitate the adjustment of 20 the shade sections and one which can be readily and easily associated with or removed from the globe as the occasion requires.

The nature and advantages of the invention will be better understood when the 25 following detail description is taken in connection with the accompanying drawings, the invention residing in the construction, combination and arrangement of parts as 30 claimed.

In the drawings forming part of this application like numerals of reference indicate similar parts in the several views, and wherein:

35 Figure 1 is a view in elevation of a lamp shade forming the subject matter of the invention, and showing the normal position of parts.

Figure 2 is a similar view showing the 40 shade sections in an adjusted position.

Figure 3 is a view showing another position of the shade sections.

Figure 4 is a view showing another manner of arranging the shade sections.

45 Referring to the drawings in detail, 10 indicates a plate which may be in the form of a reflector, having a central opening 11 from the edge of which rises an annular flange 12. This flange is provided with 50 a plurality of screws or other suitable fastening elements 13 for holding the plate associated with the globe 14, through the instrumentality of the globe attaching member or socket A. The shade together 55 with its supporting and adjusting means

is associated with the plate 10 in a manner to be hereinafter described.

The shade is made up of two identically constructed sections 15 and 16 respectively, which are hinged together as at 17 to provide for adjustment of the sections toward and away from each other. The shade is suspended from a shade support 18 of somewhat similar construction as the plate 10, through the instrumentality of chains or 60 other flexible elements 19 which have their corresponding terminals secured to the shade support 18 at diametrically opposite points. The opposite terminals of the flexible elements are secured to the respective 65 shade sections as shown. The shade support 18 is provided with a central opening to receive the globe attaching member or lamp socket A, and is arranged directly beneath the plate or reflector 10. Suspended from 70 shade support 18, are chains 22 arranged in right angular relation with respect to the chains 19, as shown in Figures 1, 2, 3 and 4 respectively, the chains 22 being utilized in holding the shade sections in any given position. For this purpose, each shade section is provided with a hook like element 23 adapted 75 to engage with any one of the links of the respective chains 22. If desired, each of 80 the chains 22 may be provided with a bell or other suitable ornament 24. Manifestly, the sections 15 and 16 of the shade can be adjusted independently or moved toward and 85 away from each other to deflect the light rays in the desired direction, when the sections are held in given position by engaging the chains 22 to hook like elements 23. The shade proper may be constructed from 90 any suitable material, and may also vary 95 in design without departing from the spirit of the invention.

While it is believed that from the foregoing description the nature and advantages of the invention will be readily apparent, 100 I desire to have it understood that I do not limit myself to what is herein shown and described and that such changes may be resorted to when desired as fall within the scope of what is claimed.

105 What I claim is:

The combination with an electric light bulb and an attaching member therefor, of a shade supporting member supported by said attaching member, chains suspended 110

from said supporting member, a shade including companion sections pivotally connected together at their lower ends, and attached to two of said chains adjacent the pivot points, said sections being susceptible to movement toward and away from each other, or as a unit wholly to one side of said bulb, a hook like element secured to each

section intermediate of its ends and slightly adjacent the upper edge thereof, and being ¹⁰ arranged to lie in path of the links of the remaining chains to engage with any given link whereby said shade may be supported in a given position.

In testimony whereof I affix my signature.
KUMA KAWAGUCHI.
